UNITED STATES PATENT OFFICE.

CARL E. SCHWESE, OF DAVID CITY, NEBRASKA, ASSIGNOR OF ONE-HALF TO FRED G. SCHWESE, OF DAVID CITY, NEBRASKA.

HOG RINGER.

Application filed April 3, 1926. Serial No. 99,557.

My invention relates to hog ringers, its object being the provision of certain additions to the hog ringers now in common use whereby the ring may be closed to a size 5 to fit hogs of various sizes. It is moreover my object to provide such simple additions to the present hog ringers that they can be manufactured and sold at a very low figure. In addition I provide a ring which 10 can be securely clinched so that it will be impossible for the ring to work loose when the hog is rooting.

Having in view these and other objects which will be mentioned in the following 15 description, I will now refer to the drawings, in which

Figure 1 is a view in side elevation showing my hog ringer, the jaws being shown in section to disclose the modification which I 20 have added to the present hog ringer.

Figure 2 is an elevation showing the interior face of one of the jaws.

Figure 3 is an illustration of one of the 25 rings which I have provided, the ring being shown open as it appears before it is inserted and clinched.

Figure 4 is a view in perspective of the body portion of the tool with the ring in place preparatory to being used.

Figure 5 is a perspective view of the 30 body portion of the tool, the jaws being partly closed with the point of the ring just entering the loop.

Figure 6 is a view in perspective of the 35 jaw portion of the tool showing the final step in the closing of the ring and the clinching of the point.

Figure 7 is an illustration of the ring as it appears when closed.

The tool which I use as the basis for my improvement consists of a pair of jaws 10 and 11 provided with handles 12 and 13 respectively and pivotally connected together by means of a pin 14. The jaw 11 has a 40 groove 11^a which extends throughout its length as shown in Figure 1. The jaw 10 is provided with side walls 10^a and with end walls 10^b, the end walls forming a B-shaped notch. In the tool as above described a ring 45 having a looped portion is inserted with the looped portion abutting against the end walls 10^b and the closing of the jaws forces the pointed end of the ring through the looped portion thereof and out through the B-shaped notch between the end walls 10^b.

Such rings are not clinched and the pointed end of the ring extends to a considerable distance outside the ring. The ring is not clinched or locked in any way and as a result the hogs frequently do enough rooting 60 to disengage the ring.

For overcoming this serious defect of the present tools, I drill an aperture through the jaw 10 and swage a plug 15 in this aperture. The plug must be at the angle indicated in Figure 1, and it should further be provided with a bevelled edge at 15^a. A slight groove 16 is also cut in the jaw 10 extending from the base of the plug 15 toward the pivot. The ring is then seated between 70 the jaws as shown in Figure 4 with its looped portion against the bevelled end 15^a of the plug 15 and against the end walls 10^b of the jaw 10. The bevelled end 15^a serves the double purpose of guiding the looped 75 portion of the ring when seating the ring and of guiding the point of the ring into the groove 16 when closing the jaws of the tool.

The ring which I employ is also a modification of the rings at present in use. In the prior rings the loop was formed by turning the wire until its end abutted against the edge of the wire. Such rings have proven to be unsatisfactory in use, since the loops frequently open either while being applied or after they have been in use for some time. To avoid this difficulty I have formed the loop by lapping the end over the wire as shown in Figure 3, the lapped 90 end being flattened. In the closing of the ring the pointed portion is passed through the loop and parallel to one side of the loop as shown in Figure 7.

The prior hog ringers are designed for 95 securing rings of different sizes to the snouts of the hogs, the size of the ring depending on the size of the hog. This necessitates that the farmer have a supply of rings of various sizes to meet any needs that may arise. The 100 tool and ring which I provide requires the use of a ring in one size only. In the ring the clinching begins as soon as the point has passed through the loop and it continues until the ring has been reduced to the 105 smallest possible size. It is therefore only necessary to close the jaws until the ring has been reduced to fit the particular animal. The tool itself has also been modified to make it possible to adjustably close the jaws 110

the required distance. For this purpose either of the handles 12 or 13, preferably the latter, is provided with a set screw 17 which may be adjusted according to the size of the animal. The adjustment can be easily made and the user has merely to pick out any one of the rings in his package, to insert the ring between the jaws of the tool as shown in Figure 4, and to close the jaws, with the assurance that the closed ring is neither too large nor too small and that it is securely locked against any possible displacement.

From the foregoing description it will be seen that I have provided a tool for clinching the ring and for closing it to any desired size, the ring being clinched for every size. Moreover, this tool is made by making a slight but exceedingly important change in the present well known hog ringgers. The adjustment is a simple matter of experience but the tool also has a feature in the set screw 17 whereby the adjustment can be quickly and easily made so that even an inexperienced person may adjustably close and clinch the ring. After the ring is applied, it remains in place until removed

with a pair of pliers, since no amount of rooting by the animal can dislodge the ring.

Having thus described my invention in such full, clear, and exact terms that its construction and operation will be readily understood by others skilled in the art to which it pertains, what I claim as new and desire to secure by Letters Patent of the United States is:

A variable clinching attachment for hog ringers having a wire curving and guiding jaw and an opposed wire loop socket jaw, comprising a plug carried by said socket jaw in the socket and inclined toward the outer end of the jaw for engagement through a wire loop in the socket and having a beveled outer corner facing the guiding jaw and adapted to receive the free end portion of a wire as the latter passes through said loop to deflect the free end portion of the wire inwardly of the jaws and beneath the inner side of the loop when said jaws are brought together.

In testimony whereof I affix my signature.

CARL E. SCHWESER.
